ABSTRACT

A *chrysanthemum* plant named 'Zanmuceles' characterized by its medium sized blooms with white ray florets and prolific branching; natural season flowering date September 9-13 (week 37); blooming for a period of 5 weeks.

3 Drawing Sheets

1

Botanical designation: *Chrysanthemum×morifolium* Ramat.
Cultivar denomination: 'Zanmuceles'.

BACKGROUND OF THE INVENTION

The present invention relates to a new and distinct cultivar of *chrysanthemum* plant, botanically known as *Chrysanthemum×morifolium* Ramat., commercially known as a garden mum, and hereinafter referred to by the cultivar denomination 'Zanmuceles'. 'Zanmuceles' is a product of a breeding and selection program for outdoor pot mums (garden mums) which had the objective of creating new cultivars with a double type inflorescence, a natural season flowering date around week 37, blooming for a period of 5 weeks. 'Zanmuceles' is a seedling resulting from a cross of the female parent id 30549 (not patented) with the male parent id 26356 (not patented). Plants of the new cultivar 'Zanmuceles' differ from plants of its parent plants in growth habit. The female parent has a more compact shape than the seedling, while the male parent is more spreading than the seedling.

The new and distinct cultivar was discovered and selected as a flowering plant by Henricus Cornelius Maria Jacobs on a cultivated field in Rijsenhout, The Netherlands in 2010. The first act of asexual production of 'Zanmuceles' was accomplished when vegetative cuttings from the initial selection in 2010 were propagated further in a controlled environment in Rijsenhout, The Netherlands. In summer, about 6-8 days are needed to initiate roots in cuttings of the new cultivar, after another 5 days rooted plants are formed. The new cultivar has been found to retain its distinctive characteristics through successive propagations.

BRIEF DESCRIPTION OF THE DRAWINGS

The present invention of a new and distinct variety of *chrysanthemum* (of about 12 weeks) is shown in the accompanying drawings, the color being as nearly true as possible with color photographs of this type.

2

FIG. 1 shows a plant of the cultivar in full bloom.
FIG. 2 shows the various stages of bloom of the new cultivar.

FIG. 3 shows the various stages of foliage of the new cultivar.

DESCRIPTION OF THE INVENTION

The observations and measurements were gathered from 10 plants, in the period of 11 to 18 weeks of age, grown outdoor in Rijsenhout, The Netherlands under natural day length and temperature and planted in week 23 in 2013 (with a warm summer), receiving drip irrigation. The natural blooming date of this crop was September 9-13 (week 37). The average height of the plants was 40-45 cm. No growth retardants were used. No tests were done on disease or insect resistance or susceptibility. No tests were done on cold or drought tolerance. This new variety produces medium sized blooms with white ray florets blooming for a period of 5 weeks.

From the cultivars known to the inventor the most similar existing cultivar in comparison to 'Zanmuceles' is 'Crete' (U.S. Plant Pat. No. 16,677). When 'Crete' and 'Zanmuceles' are being compared the following difference is noticed: The 25 difference of 'Crete' and 'Zanmuceles' are (1) Inflorescence size. And (2) Inflorescence color. (1). Inflorescences of 'Crete' are smaller than those of 'Zanmuceles'. (2) The inflorescences of 'Crete' are cream colored, while those of 'Zanmuceles' are pure white.

30 The following is a description of the plant and characteristics that distinguish 'Zanmuceles' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, 5th edition 2007.

TABLE 1

Botanical Description of <i>Chrysanthemum × morifolium</i> Ramat. 'Zanmuceles'	
Bud	
Size:	Small; cross-section 5-6 mm, height 4 mm
Shape:	Round
Texture:	Pubescent
Outside color:	Greyed-green 191A
Phyllaries	
Number:	21, arranged in 3 rows
Shape:	Elliptic
Apex:	Acute
Base:	Truncate
Margin:	Entire
Color:	Upper side: Green N138A Lower side: Green 138A
Length and width:	5-6 mm; 1.5-2 mm
Texture:	Pubescent
Inflorescences	
Type:	Double
Height:	1.8 cm
Diameter:	5 cm
Peduncle length:	10-12 cm
Peduncle color:	Green 138B
Peduncle diameter:	1.5 mm
Peduncle texture:	Pubescent
Peduncle strength:	Weak
Number per branch:	About 5-6 .inflorescences
Duration of flowering:	5 weeks
Seeds:	Produced in small quantities, ovate, Greyed-brown 199A, length 1.5 mm, diameter 0.5 mm; texture: rough with ribs
Fragrance:	Faint chrysanthemum odor
Color inflorescences	
Center of inflorescence:	Immature stage: White 155A; Mature stage: White 155A
Color of upper side of ray florets:	White NN155D
Color of lower side of ray florets:	White NN155D
Tonality from distance:	A garden mum with white blooms and a cream center
Color of ray florets after aging of the plant:	White 155D
Ray florets	
Type:	Ligulate
Texture:	Upper and lower side smooth
Number:	190-210
Shape:	elliptic
Apex:	dentate
Base:	attenuate
Cross-section:	flat
Longitudinal axis:	reflexing
Length of corolla tube:	3-5 mm
Diameter corolla tube:	1-1.5 mm
Ray floret margin:	Entire
Ray floret length:	1.5-2.5 cm
Ray floret width:	1-5 mm
Ratio length/width:	High
Disc florets	Absent
Receptacle	
Color:	Yellow-green 145D
Shape:	Conical raised
Height:	4 mm
Diameter:	3 mm
Reproductive Organs	
Androecium:	Absent
Pollen:	Absent
Gynoecium:	Present on ray florets

TABLE 1-continued

Botanical Description of <i>Chrysanthemum × morifolium</i> Ramat. 'Zanmuceles'	
5	Style color: Yellow-green 154C Style length: 4 mm Stigma color: Yellow 7A Stigma width: 1 mm Ovary: Enclosed in calyx; color: Yellow-green 149D
10	Plant
15	Type: Bushy Growth habit: Spherical shape Growth rate: Medium to High Height: 40-45 cm Width: 55-65 cm Stem color: Greyed-brown 199A Stem strength: Weak Stem brittleness: Brittle Stem anthocyan coloration: Absent Internode length: 1-2.5 cm Length of lateral branch: From top to bottom 22-25 cm 20 Lateral branch color: Green 137 C Lateral branch, attachment: weak Lateral branch diameter: 2.5 mm Lateral branch texture: Pubescent with ribs Branching (average number of lateral branches): Dense with 8 breaks after pinching
25	Natural season blooming date: Sep. 9-13 (week 37) in Rijsenhout, The Netherlands Roots-habits: Fine, freeing branching Roots-color: White 155D Foliation
30	Glossiness: Leaf upper side: weak Leaf lower side: very weak Leaf color: Upper side: Green 138A Lower side: Green 138B Color midvein: Upper side: Yellow-green 147D Lower side: Yellow-green 148D
35	Size: Small; length 2-3.5cm, width 1-1.3 cm Quantity (number per lateral branches): 24-26 Shape: Elliptic Texture upper side: Sparsely pubescent Texture under side: Pubescent
40	Venation arrangement: Palmate Shape of margin: Serrated Shape of base of sinus between lateral lobes: Rounded Margin of sinus between lateral lobes: Diverging Shape of base: Acute
45	Apex: Mucronulate Petiole attitude: Moderately upwards Petiole length: 0.3-0.5 cm Petiole diameter: 2-3 mm Petiole color: Yellow-green 147D Stipule: Small, 1 mm
50	

TABLE 2

Differences with the comparison variety, when grown under identical conditions			
55	'Zanmuceles'	'Crete'	
60	Inflorescence size Color upper side ray florets	5 cm White NN155D	3 cm White 158D

I claim:

1. A new and distinct *chrysanthemum* plant named 'Zanmuceles' as described and illustrated.
